FLUORESCENT AGENTS AND PROCESS OF
MAKING THE SAME

James W. Libby, Jr., Dexter B. Pattison, and Frithjof Zwilgmeyer, New Castle County, Del., assignors to E. I. du Pont de Nemours & Company, Wilmington, Del., a corporation of Delaware

No Drawing. Application October 31, 1952,
Serial No. 318,106

7 Claims. (Cl. 260—247.1)

This invention relates to novel organic compounds. More particularly, this invention deals with novel compounds which correspond to the general formula

wherein R₁ represents H or CH₃; R₂ and R₃ individually represent lower alkyl or hydroxy-alkyl (for instance, methyl, ethyl or hydroxyethyl) or jointly represent the oxydiethylene radical

which completes with the N-atom a morpholine ring; R₄ and R₅ individually represent hydrogen, alkyl or hydroxy-alkyl, or jointly represent the oxydiethylene radical above indicated.

It is an object of this invention to produce fluorescent agents having good affinity for nylon fiber, moderate to good affinity for cotton fiber, and good resistance to bleach. Various additional objects and achievements of this invention will appear as the description proceeds.

So called "optical bleaching agents" for cotton have been known for some time. They are generally water-soluble compounds having a natural affinity for cotton, and are applied thereto from aqueous solution, in a manner similar to the application of dyes. The action of the ultra-violet wave lengths present in daylight then excites a bluish fluorescence in the "dyed" fiber, which overcomes any natural yellowishness in the fiber and gives the latter a brilliant-white appearance.

To be applicable also to hydrophobic fiber, for instance nylon or cellulose acetate, it is essential that the fluorescent dye be free of water-solubilizing groups, such as sulfo or carboxy. Thus, the requirements of affinity for hydrophobic fiber and affinity for cotton are in a sense incompatible.

It has also been known that whereas 2-p-aminophenylbenzothiazoles in general have affinity for the one fiber or the other and act thereon as optical bleaching agents, many compounds of this series turn yellow upon the fiber if the latter is treated with chemical bleaching agents, such as sodium hypochlorite. This of course would defeat the very purpose of treating the fiber with the optical bleaching agent.

We have now discovered that compounds of the general formula hereinabove have good affinity for nylon fiber, moderate to good affinity for cotton fiber and good resistance to bleach, in that they will not turn yellow when treated with sodium hypochlorite. The affinity for cotton

2

will generally be greater the less the molecular weight of the compound. Accordingly, the preferred compounds for the purpose of this invention are those compounds of the above general formula in which the sum of the carbon atoms in R₁, R₂, R₃, R₄ and R₅ does not exceed 10.

Some individual members of this group have various additional desirable properties. For instance, those subjected by us to dermatological tests have been found to be non-toxic and safe in this respect.

Accordingly, our invention opens up a new field in the art of whitening nylon or cellulose acetate with optical bleaching agents.

The preparation of our novel compounds may follow several distinct procedures, of which the following are typical:

1. Chlorosulfonylation of an unsulfonated p-dimethylaminophenyl-benzothiazole compound, followed by amidation.
2. Chlorination of a sulfonated p-dimethylaminophenyl-benzothiazole to convert the SO₃H group into SO₂Cl, followed by amidation.
3. Synthesis from a p-dialkylamino-benzaldehyde and an ortho-amino-phenyl mercaptain which already possesses a sulfonamide group.
4. Chlorosulfonylation of a p-acetylaminophenyl-benzothiazole, followed by amidation in the SO₂Cl group, hydrolysis of the acetyl group, and alkylation in the p-amino N-atom.

Without limiting our invention, the following examples will serve to illustrate our preferred embodiments thereof. Parts mentioned are by weight.

EXAMPLE 1

35 Fifty parts of N,N-dimethyl-dehydrothio-p-toluidine (prepared by methylation of dehydrothio-p-toluidine with methanol and HCl by well known methods) were added to 350 parts of chlorosulfonic acid below 8° C. and the mixture was heated three hours at 90° C. After cooling, the reaction mixture was added to ice and water below 5° C. The acid chloride was filtered off, washed with ice water, and divided into three equal portions. One of these portions was added to 90 parts of 27% ammonia below 10° C. and stirred overnight at 25° C. After acidification with hydrochloric acid, the N,N-dimethyl-dehydrothio-p-toluidine sulfonamide was isolated by filtration, washed with water, and dried.

The other two portions were likewise treated, respectively, with monomethylamine in methyl alcohol solution and with monoethanamine in ethyl alcohol, to yield the N-methyl and the N-hydroxyethyl sulfonamides.

Properties of the three compounds obtained are tabulated below. The melting points were taken after recrystallization from cellosolve.

65	R	M. P., ° C.	U. V. Ab-sorption maximum (mu)	Percent Sulfur	
				Anal.	Theory
	H	252-254	3,640	18.57	18.38
	CH ₃	192-194	3,680	17.70	17.75
70	—CH ₂ CH ₂ OH	188-190	3,690	16.30	16.38

All three sulfonamides are powerful whitening agents

for textile fibers. When dimethyldehydrothio-p-toluidine sulfonamide is applied to cotton from a detergent bath it is approximately equal in whitening power to the best whitening agents now on the market. In addition, dimethyldehydrothio-p-toluidine sulfonamide, in small quantities, is an effective whitening agent for nylon, silk, cellulose acetate, and wool.

EXAMPLE 2

A mixture of 25 grams of 2-(p-dimethylaminophenyl)-benzothiazole and 100 cc. of chlorosulfonic acid was heated four hours at 100° C., 2 hours at 120° C., and three hours at 150° C., until a spot test showed nearly complete solubility in dilute aqueous alkali. The charge was cooled, and drowned in ice and water below 5° C. The acid chloride was filtered off, washed with ice water, and stirred overnight with ammonia. After acidification, the product was filtered off, washed and dried. Recrystallization from ethylene-glycol-monoethyl ether gave 2-(p-dimethylaminophenyl)-benzothiazole sulfonamide, which had a melting point of 279°-282° C. This compound was a powerful whitening agent for textile fibers.

The initial intermediate required for this example is a known compound. See, for instance, Bogert and Taylor, Chem. Abst., vol. 26, p. 1281.

EXAMPLE 3

A mixture of 77 grams of 2-(p-dimethylaminophenyl)-benzothiazole sulfonic acid and 200 cc. of chlorosulfonic acid was heated 2 hours at 90°-95° C. The reaction mass was then cooled to 24° C. and drowned in ice. The sulfonic acid chloride was filtered and washed nearly acid-free with ice water. The wet filter cake was agitated over night at room temperature with a large excess of 27% aqueous ammonia. The sulfonamide slurry was then acidified with hydrochloric acid and filtered, after which the 2-(p-dimethylaminophenyl)-benzothiazole sulfonamide was washed thoroughly with water and dried. The product appeared to be identical with that obtained in Example 2.

By reacting, similarly, the 2-(p-dimethylaminophenyl)-benzothiazole sulfonyl chloride with aqueous methylamine and ethanalamine dissolved in ethanol, the corresponding N-methyl and N-hydroxyethyl sulfonamides were obtained.

All of these sulfonamides are powerful whitening agents for nylon, cellulose acetate, wool and cotton.

The initial material for this example was prepared by drying the free monosulfonic acid filter cake obtained according to Example 1 of co-pending application of F. Zwilgmeyer, Serial No. 299,260 (Patent No. 2,715,629, issued August 16, 1955).

EXAMPLE 4

Step 1.—A mixture of 118 grams of 4-chloro-3-nitrobenzenesulfonamide and 472 cc. of ethylene-glycol monoethyl ether was heated to 100° C., and a sodium disulfide solution, made from 62.5 grams of sodium sulfide crystals, 8.3 grams of sulfur, and 60 cc. of water was added at 90°-100° C. After heating three hours at 90°-95° C., the solid was separated by hot filtration, washed with water, and dried. It constituted 2,2'-dinitrophenyldisulfide-4,4'-disulfonamide.

Step 2.—A mixture of 60 grams of the diphenyldisulfide obtained in Step 1, 116 grams of sodium sulfide crystals, and 400 cc. of water was heated at reflux for four hours, and acidified with hydrochloric acid until barely acid to Congo red paper. The 3-amino-4-mercaptopbenzenesulfonamide was filtered off, washed with 10% NaCl solution, and dried.

Step 3.—A mixture of 25.5 grams of the 3-amino-4-mercaptopbenzenesulfonamide obtained above, 3.2 grams of sulfur, 13.7 grams of p-dimethylaminobenzaldehyde, and 60 cc. of o-dichlorobenzene was agitated and heated one half hour at 140°-160° C. After cooling, the product

was filtered off and washed with alcohol. Recrystallization from ethylene-glycol-monoethyl ether gave light yellow crystals of 2-(p-dimethylaminophenyl)benzothiazole-5-sulfonamide having a melting point of 292°-294° C. This compound is a good whitening agent for nylon, cellulose acetate, and cotton.

The successive reactions involved in the above procedure may be summarized as follows:

The final product is apparently an isomer of that obtained in Examples 2 and 3.

EXAMPLE 5

Ten parts of 2-(4'-morpholinyl-phenyl)-benzothiazole (prepared by first reacting N-phenyl morpholine with POCl_3 and formamide according to U. S. P. 2,558,285, followed by heating the resulting p-morpholinyl-benzaldehyde with an equimolecular amount of o-aminothiophenol, in the presence of 1-atom equivalent of sulfur at 170° C. for 2 hours) were added to 180 parts of chlorosulfonic acid at 0°-8° C. and then heated at 90° C. for 3 hours. The chlorosulfonation mass was then cooled and drowned below 5° C. in iced water. The precipitated sulfonchloride was filtered and washed with ice water until nearly acid-free. The filter cake was added to 100 parts of 20% aqueous dimethylamine solution at 0° C. and agitated for 16 hours allowing the temperature to rise to 25° C. The reaction mass was then neutralized with hydrochloric acid, filtered, and the product washed with water and dried. The product is a nearly white solid, having presumably the formula

Fabrics treated with this product by the method described in Example 9 hereinbelow exhibited an intense whitish-blue fluorescence when exposed to ultra-violet light.

EXAMPLE 6

Twenty parts of 2-(4'-dimethylaminophenyl)-6-methylbenzothiazole were added to 143 parts of chlorosulfonic acid with agitation at 0°-10° C. The mixture was then heated slowly to 130° C. and held at that temperature for 1 hour. The reaction mass was then cooled to room temperature and drowned in ice. The yellowish product which separated was filtered off and added to a mixture of 60 parts of diethylamine and 120 parts of ethanol at 0°-10° C. After stirring at this temperature for two hours, the mixture was slowly brought, with stirring, to room temperature. The cream colored product was filtered off, slurried in a mixture of 20 parts of sodium carbonate in 200 parts of water, and again filtered off. It was then slurried in 100 parts of ethanol, again filtered off, and dried at 75° C.

The 2-(4'-dimethylaminophenyl)-6-methyl-benzothiazole diethylsulfonamide thus obtained was soluble in

alcohol and in acetone; and the resulting solutions exhibited an intense bluish-white fluorescence, when exposed to ultra-violet radiation.

EXAMPLE 7

Example 6 was repeated except that the solid product resulting from drowning the first reaction mass in ice was filtered off and added to a mixture of 80 parts of morpholine and 160 parts of ethanol at 0°-10° C. After stirring for two hours at 0°-10° C., the mixture was 10 agitated over night and allowed to warm up to room temperature. The resultant cream colored product was filtered off and purified from aqueous sodium carbonate, then ethanol, and dried as described in Example 6.

2 - (4' - dimethylamino - phenyl - 6 - methyl benzothiazole morpholinyl sulfonamide was thus obtained, whose solutions in alcohol or acetone exhibited an intense bluish-white fluorescence when exposed to ultra-violet radiation.

EXAMPLE 8

20 parts of 2 - (4' - dimethylaminophenyl) - 6 - methyl benzothiazole was treated with 143 parts of chlorosulfonic acid as in Example 6. The reaction product was cooled to room temperature, then drowned in ice. The resulting solid product was filtered off, and added to a mixture of 200 parts of ethanol and 105 parts of diethanolamine at 0°-10° C. The mixture was stirred for two hours at 0°-10° C., then allowed slowly, with stirring, to rise to 20°-25° C. The cream colored 2-(4'-dimethylaminophenyl)-6-methyl benzothiazole diethanol sulfonamide was filtered off, purified by slurring in sodium carbonate and alcohol as in Example 6, and dried at 75° C. Solutions of the product in alcohol or acetone exhibited an intense bluish-white fluorescence when exposed to ultra-violet radiation.

The following additional example describes a method for using the foregoing whitening agents.

EXAMPLE 9

Soap containing 0.02% of the 2-(p-dimethylaminophenyl)-6-methyl benzothiazole sulfonamide of Example 1 was prepared by mixing 60 grams of a neutral fatty acid soap and 100 cc. of water in a colloid mill until a smooth slurry was obtained, followed by the incorporation of a solution of 0.012 grams of said whitening agent in 60 cc. of methanol and thereafter drying the mixture on a rotary drum drier at 100° C. The soap flakes thus obtained were ground to 40 mesh. The resulting soap powder showed an intense whitish-blue fluorescence when exposed to ultra-violet light.

A dye bath was made by dissolving 0.4 gram of the treated soap in 100 cc. of water at 130° F. A 2 gram piece of cloth was "dyed" in this bath by conventional methods, and dried. Nylon, cellulose acetate, and cotton cloths dyed in this fashion were considerably whiter than untreated control samples.

In manners similar to the above examples, various other compounds within the scope of this invention may be readily prepared. In particular, the p-dimethylaminophenyl-benzothiazoles where mentioned in the above examples, may be replaced by the corresponding p-diethylamino-, p-(ethyl-methylamino)- or other lower p-dialkylamino-phenyl derivatives of benzothiazole and 6 - methyl - benzothiazole. The monosulfo - p - (dimethylamino-phenyl)-benzothiazole of Example 3 may be replaced by the corresponding p-diethylamino-, or p-ethyl-methylamino-phenyl derivatives of Zwilgmeyer's copending application above identified.

The amine for amidation of the SO₂Cl group in the several examples above may be ammonia, monomethylamine, monoethylamine, monoethanolamine, dimethylamine, ethylmethylamine, diethylamine, diethanolamine, monomethyl-monoethanolamine, monoethyl-monoethanolamine, or morpholine. Or, one may start with a corresponding sulfonamido-3-nitro-4-chloro-benzene as in 75

Example 4, and condense the thiazole following Step 2 with an optional p-dialkylamino-benzaldehyde in which the alkyl groups possess 1 to 4 C-atoms each.

Compounds having hydroxyethyl groups in the p-amino N-atom are best prepared by the method indicated under the numeral 4 in the above general discussion. For instance, N-acetyl-dehydrothioparitoluidine (made by acetylation of dehydrothioparitoluidine) is reacted with chlorosulfonic acid and then with dimethylamine as in Example 1, to give N-acetyl-dehydrothioparitoluidine sulfone-dimethylamide. The acetyl group is then hydrolyzed off by the aid of dilute mineral acid, and the resulting primary amine is reacted with ethylene oxide in an autoclave to give the corresponding di(hydroxyethyl) compound.

Numerous other variations in the details of procedure will be readily apparent to those skilled in the art.

We claim as our invention:

1. A compound of the general formula

25 wherein R₁ represents a member of the group consisting of hydrogen and methyl, the grouping

30 represents a radical of the group consisting of dialkylamino, monoalkyl-mono(hydroxyalkyl)-amino, di(hydroxyalkyl)amino and morpholino, while the grouping

35 represents a radical of the group consisting of primary amino, monoalkylamino, dialkylamino, mono(hydroxyalkyl)amino, monoalkyl-mono(hydroxyalkyl)amino, di(hydroxyalkyl)amino and morpholino, all the alkyl radicals being radicals of not more than 4 C-atoms each, and the total number of carbon atoms in R₁, R₂, R₃, R₄ and R₅ being not greater than 10, said compounds being fluorescent agents having affinity for nylon fiber.

40 2. A primary sulfonamide of N,N-dimethyl dehydrothio-p-toluidine.

3. A primary sulfonamide of 2-(p-dimethylaminophenyl)-benzothiazole.

45 4. 5-sulfonamido - 2 - (p-dimethylaminophenyl)-benzothiazole.

5. A dimethylsulfonamide of 2-(p-morpholinophenyl)-benzothiazole.

6. A process of producing a fluorescent agent, which comprises reacting chlorosulfonic acid with a p-amino-benzothiazole compound of the formula

70 wherein R₁ represents a member of the group consisting of hydrogen and methyl, while the grouping

represents a radical of the group consisting of dialkylamino, monoalkyl-mono(hydroxyalkyl)amino, di(hydroxyalkyl)amino and morpholino, and then reacting the inter-

mediate chlorosulfonyl compound thus produced with a base selected from the group consisting of ammonia, monoalkyl and dialkyl amines, mono(hydroxyalkyl) amines, monoalkyl-mono(hydroxyalkyl) amines, di(hydroxyalkyl) amines and morpholine, all the alkyl radicals aforementioned being radicals of not more than 4 C-atoms each.

7. A process of producing a fluorescent agent, which comprises reacting chlorosulfonic acid with N,N-dimethyl-

dehydrothio-p-toluidine, and then reacting the resulting chlorosulfonyl compound with ammonia, whereby to convert the same into the corresponding sulfonamide.
